METAL PERFORATING MACHINE

Albert V. Pickering and Frank W. Willis, Fitchburg, Mass., assignors to Multi-Products, Inc., Fitchburg, Mass., a corporation of Massachusetts

Application January 18, 1932, Serial No. 587,306
Renewed November 14, 1935

1 Claim. (Cl. 33—25)

This invention relates to a machine for perforating sheet metal for the purpose of forming designs for use on signs, stencils and various other purposes.

The principal objects of the invention are to provide a pantograph arrangement by which an operator can move a pointer over a pattern and the work will be moved in accordance with the motions of the pointer to bring a cutter, operating at a single point, over the various parts of the sheet to reproduce the design traced by the pointer; to provide a simple and sufficiently strong arrangement for so moving the work; to provide a table on which the pattern is located and having a part for supporting the sheet and a perforation or die to allow the cutting tool to pass through the work at a stationary point on the table, thus securing a die cutting action; to provide means for easily disconnecting the motor or other source of power from the operating cutter, and to provide improvements in the various features of the machine.

Other objects and advantages of the invention will appear hereinafter.

Reference is to be had to the accompanying drawings in which

Fig. 1 is a plan of a machine constructed in accordance with this invention;

Fig. 2 is an end elevation; and

Fig. 3 is a sectional view showing parts of the frame in side elevation, as indicated by the line 3—3 in Fig. 1.

The invention is shown in a form in which the table 10 is mounted at a suitable height on a series of posts 11 with cross pieces 12, the same constituting the main part of the frame. This table is of sufficient area to support a pattern 14 in any desired position. This pattern is secured to the wooden table by thumb-tacks or other fastening devices on the table and is provided with a design 15 which is shown in the present instance as representing the capital letter E. On the table is a comparatively thick metallic sheet 13 on which the work in the form of a sheet of metal 16 is adapted to rest and to slide as will appear.

The pattern 15 is intended to be traced along the lines which are to be cut into the work 16 by a pointer 17 having a handle by which the workman operates it. This pointer is mounted on an arm 18 to which it is rigidly connected. To this arm is secured a movable rod 19 extending along the machine in the direction of its length and over the table. The rod is supported to move on the table top by a slide 29.

On this rod is fixed a collar 20 and a brace or tie 21 passes from that to the arm 18 near the pointer at an angle. The parts 18, 19 and 21 constitute a rigid triangular frame and the movements of the pointer of course are imparted to this triangle and it necessarily moves with the pointer. Pivoted connected with the rod 19 are two or more rods 22, these being connected by vertical pivots 23 so that these rods will be capable of swinging about two axes at right angles to each other. These rods are also provided with vertical pivots 24 at their opposite ends. By these pivots the rods are connected with pivot pieces 25 pivotally mounted at the upper ends of links 27 which are pivoted on a rod 28 extending throughout the length of the machine at the bottom. This rod 28 is mounted to turn in stationary bearings supported by the framework near the bottom of the machine. Connected with the rod 28 or the links 27 are a series of counterweights 30 for normally holding the whole pivoted structure back slightly so that there will be some resistance to the motions which the operator imparts to the pointer 17.

On account of the pivotal mountings in this pantograph frame, it will be seen that the pointer can be moved to any point on the pattern 14, that is, in a plane, and this whole frame will have to move with it. Furthermore, the rod 19 is reciprocated to move in parallelism with itself at all times and cannot get into a skewed position. The rods 22 can move upwardly as shown in Fig. 2 and sideways about their pivots, as shown in Fig. 1, to permit of the necessary movements. On the rod 19 beyond this pantograph frame are a pair of brackets 31 each having a base 32 and a movable clamping plate 33 together with a screw 34 for forcing the clamping blade down to grip the edge of the work 16. It will be seen therefore that the work moves with the pointer and necessarily has a parallel motion.

Supported on two posts 40 is a motor 41 or other source of power.

The cutter shaft 46 is mounted in a head 47 in alignment with the motor shaft.

For the purpose of stopping the rotation of the cutter shaft without stopping the motor, a pedal 52 is provided which is connected by a link 53 with a lever 54 in turn connected with a rod 55. This rod is pivotally connected with a bell crank 56 which is normally pulled inwardly at the top by a spring 57.

On the shaft 46 there is an eccentric 63 which cooperates with an eccentric strap 64 to reciprocate a plunger 65. This plunger carries a cutting

5 tool 66 which obviously reciprocates along a vertical line. The plunger 65 is mounted in bearings on a downward extension on the head 47. The head 47 also is provided with a rod 68 extending downwardly and having a foot 69 on the bottom. This foot is horizontal and is provided with a notch 70 through which the cutter 66 operates. This foot is for the purpose of holding down the sheet 16 at all points around the cutter and keeps it from shifting or flexing while the cutter is operating. The table 10 is provided with a die or metallic thimble 72 for receiving the cutter. The top surface of this is rounded and it just engages the sheet 16 so as to furnish 10 a solid backing for it at the point of cutting, the cutter being shaped with vertical sides, it will cut out pieces of sheet metal or other material and force them down through this member 15 72, thus constituting a die cutting apparatus. 20 The chips fall down through an opening 73 in the table 10.

25 It will be seen therefore that the operator can manipulate the pointer 17 by hand and will at the same time move the sheet 16 exactly in parallelism at all times and that the cutter works at all times at a single spot so that the design followed by the pointer 17 will be reproduced in the sheet in the form of a line of perforations through it. As the cutter is reciprocated so rapidly and the work moved so slowly, they will constitute a continuous unbroken line. All the movements of the pointer are reproduced by the sheet 30 and therefore the design is reproduced accurately.

When it is desired to start the cutter, the treadle 52 is depressed and, whenever it is desired to stop, it can then be released and the spring 57 will withdraw the pin 59 so as to disconnect the clutch. This is a very simple machine which reduces the time taken to cut out any of a design in a sheet of metal or other material. 5

10 Although we have illustrated and described only one form of the invention, we are aware of the fact that modifications can be made therein by any person skilled in the art without departing from the scope of the invention as expressed in the claim. Therefore, we do not wish to be limited to all the details of construction herein shown and described, but what we do claim is:— 15

20 In a pantograph for a cutting machine, the combination with a table adapted to support a design to be copied and a movable sheet in which the design is to be reproduced, of a pointer adapted to be moved by hand over the design, a member 25 resting freely on the table to which member the pointer and sheet are rigidly fixed to move therewith, parallel rods pivoted to said member so as to move vertically and horizontally relative to said member, and an equal number of parallel links pivoted below the table top on a horizontal axis and pivoted to the rods so as to move vertically and horizontally relatively thereto, whereby said member will be constrained to move parallel to the movement of the pointer. 30
